UNITED STATES PATENT OFFICE.

SALVATORE SCOGNAMILLO, OF NEW YORK, N. Y., ASSIGNOR TO LIBERTY OIL BURNER CO., INC., OF NEW YORK, N. Y., A CORPORATION OF NEW YORK.

HIGH-PRESSURE VAPOR OIL BURNER.

Application filed January 9, 1924. Serial No. 685,113.

To all whom it may concern:

Be it known that I, SALVATORE SCOGNAMILLO, a citizen of the United States, residing at New York, in the county of New York and State of New York, have invented new and useful Improvements in High-Pressure Vapor Oil Burners, of which the following is a specification.

This invention relates to a high pressure oil burner organization, and the primary object of the invention is to provide a burner of the class specified adapted either for domestic or general commercial use or in connection with steam boilers, either stationary or of the locomotive type, and adapted to be installed in a domestic furnace without in the least modifying the grate or fire box organization of the latter, or in connection with grates of stationary steam boilers and locomotive or other portable boilers without material modification of the usual features of construction in the latter devices. A further object of the invention is to provide a high pressure volatile oil burner of a comparatively simple construction and arrangement of parts wherein an automatic operation ensues as to the volatilization of a hydrocarbon product such as crude oil and the generation of dry steam, which is commingled with the oil vapor, with obvious advantages in combustion and resultant practical service in the production of an intense heating flame, which ensues at various locations regularly over the surface of the burner. A further object of the invention is to provide a self-acting high pressure volatile oil burner having a simple organization of devices therein of an inexpensive character for thoroughly and effectively volatilizing a hydrocarbon product and forming and drying steam for mixture with the vapor of the hydrocarbon product, without requiring manual attention after the improved burner organization has started its operation and to which oil and water will be regularly and automatically supplied in requisite quantities to replace the reduction of the primary charges of oil and water due to the formation of vapors and dry steam. A further object of the invention is to so construct all of the parts of the improved high pressure volatile oil burner that they may be readily assembled at a comparatively small cost and also permitting an easy separation and dismem-

berment of the burner units for cleaning purposes, and furthermore, to render the complete organization compact in its general dimensions but with sufficient chamber space therein to effectively carry on the formation of hydrocarbon vapors and dry steam and regularly feed the latter to the burner units. A still further object of the invention is to generally improve burners of the type specified and minimize the cost of production and installation thereof for practical service, and thereby also economize in the use of fuel in both domestic and commercial heating plants.

With these and other objects and advantages in view, the invention consists in the preferred construction and arrangement of parts which will be more fully hereinafter described and claimed.

In the drawings:

Fig. 1 is a top plan view of a burner organization embodying the features of the invention and shown partially broken away;

Fig. 2 is a front end elevation showing the automatic oil and water feeding devices broken away to illustrate the internal arrangement thereof; and

Fig. 3 is a side elevation partially in section of the improved burner organization.

The numeral 5 designates the main or essential element of the improved burner or burner organization, consisting of a substantially rectangular body preferably composed of sections 6 and 7 of cast metal having contiguous flanges 8 tightly joined by suitable fastening means such as bolts 9. The element 5 is a multiple chamber device comprising a lower water chamber 10, a dry steam chamber 11 directly over the chamber 10, and an oil chamber 12. The chambers 10 and 11 are embodied in the lower section 6, and the chamber 12 is located in the upper section 7. The water chamber 10 is materially larger than the remaining chambers 11 and 12 and the chamber 11 is reduced in vertical extent so as to confine the dry steam therein and conserve the pressure of said steam. The upper section 7 has a top plate or covering 13 formed at regular intervals with a plurality of openings 14 surrounded by internally screw-threaded collars 15, the openings 14 and collars 15 being disposed at regular intervals and in symmetrical positions over the top

plate 13. The bottom 16 of the chamber 12 also has a plurality of openings 17 formed therethrough and surrounded by internally screw-threaded collars 18, the openings 17 and collars 18 being of materially less diameter than the openings 14 and collars 15 directly thereabove. The top plate 13 of the chamber 12 at two points has openings 19 therein surrounded by collars 20, and below the latter openings and collars the bottom plate 16 of the chamber 12 has two openings 21 therein and also surrounded by collars 22 projecting upwardly into the chamber a suitable distance above the bottom plate 16. Connected to the front end 23 of the chamber 10 by means of suitable collars 24 and connecting devices 25 and opening into the said chamber are vertically disposed wet steam conveying pipes 26 having rearwardly extending conveying pipes 27 of smaller diameter and connected to the upper ends thereof by suitable connecting devices 28 and continuing in the form of further diametrically reduced pipes 29 and 30, respectively extending forward and rearward in looped form and united by connecting devices 31 and 32. The rear ends of the rearwardly extending reduced pipes 30 are united by connecting devices 33 to vertically disposed branch pipes 34 extending through the openings 19 within the collars 20 and secured in the openings 21 within the collars 22 and fully opening into the upper portion of the dry steam chamber 11. The vertical branch pipes 34 are imperforate and as shown by Fig. 3 pass through the oil chamber 12.

As shown by Fig. 2, an oil supply pipe 35 is connected with and opens into the chamber 12. To the lower portions of the unions 25 a water supply pipe 36 is connected and the oil supply pipe 35 and water supply pipe 36 are also connected to the bottoms of oil and water supply reservoirs 37 and 38, the pipes 35 and 36 having valves 39 and 40, for regulating or cutting off the flow of the oil and water from the reservoirs 37 and 38 as may be found necessary. The oil and water reservoirs 37 and 38 are adapted to be located any suitable distance from the improved burner organization and each has a central rod 39' disposed therein for operation therewith of a float 40', the float being fixed to the rod and the latter vertically movable in suitable guide devices as, for instance, a bracket arm 41 as shown in the reservoir 38, and lower guides 42 at the bottom of each of the reservoirs, it being understood that the bracket arm 41 may be duplicated in the reservoir 37. On each rod are a pair of collars 43 between which the inner end of a lever 44 is mounted and intermediately fulcrumed on an ear or lug 45 projecting from a supply valve casing 46 having a discharge outlet 47 and a spring-

actuated valve stem 48 rising from the top thereof and formed with a rounded head 49 on which the free end of the lever 44 has bearing. The valve within the casing 46 may be of any suitable type, such, for instance, as a vertically movable plug valve, and connected to one side of the supply valve 46 is a supply pipe 50, which projects outwardly through the side of the reservoir. This construction is also duplicated in the reservoir 38, the rod 39' in the latter reservoir being shorter than the said rod in the reservoir 37 in view of the different horizontal locations of the two chambers 10 and 12 with which the respective reservoirs 38 and 37 are connected. The supply pipes extending outwardly from the supply valves 46 will be respectively connected to a suitable oil and water supply and it will be seen that the level of the water and oil in the reservoirs 38 and 37 is the same as the level of the water and oil in the chambers 10 and 11, as indicated by dotted lines in Figs. 2 and 3 and also partially in full lines in the latter figures. It is intended that the predetermined level of the water and oil in the chambers 10 and 12 be uniformly maintained through the automatic operation of the float and supply valve mechanism in the reservoirs 38 and 37. The reservoirs 37 and 38 are also preferably closely arranged as shown by Fig. 2 and may be one structure divided by a central partition. However, the exact manner of forming these reservoirs and positioning the same may be varied at will, and also the automatically operating means therein for maintaining a uniform level of the water and oil in the chambers 10 and 12. As shown, the reservoirs 37 and 38 have a common top cover or plate 51, and it will be further understood that the pipes 35 and 36 connected to the bottom portions of these reservoirs will be of any length desired and have a general contour that may be necessary in making connection with the chambers 10 and 12.

Below the bottom of the water chamber 10 an oil conveying pipe 52 is disposed and transversely looped or bent as illustrated by Fig. 1, to increase the circulation of the oil or cause the latter to have as long a conveyance as possible beneath the water chamber and at the rear end of the burner organization this pipe 52 is continued in the form of a vertical branch 53 a suitable distance above the top of the plane of the oil chamber 12 and then regularly projected forwardly and rearwardly in the form of vaporizing loops 54, the uppermost loop being continued forwardly a greater distance than the loop below and connected to a vertical pipe 55, which opens through the top 56 of a regulator 57. This regulator and the looped pipes 54 may or may not be used, as desired, in view of the fact that the con-

veying oil pipe 52 connects with the pipe 35 by a union 58 and in simplified installations the said upper vaporizing loop 54 with its connecting pipe 53 and conveying pipe 52 together with the regulator 57 will be omitted. In large commercial installations, however, it will be preferred to use these parts that are omitted in more simplified installations. It may also be found necessary in some installations to dispense with the operation of the vaporizing coil 54, its connection 53 and the conveying pipe 52, and if such be the case, the supply of oil may be shut off from the conveying pipe through the medium of a valve 59 located adjacent to the union 58. The regulator 57 may also be of any preferred type, but one practical form thereof is shown by Fig. 3 and consists of an outer casing or shell 60 having a lower rounded bottom 61 and therein is fitted a valve case 62 of less diameter than the shell, said valve case having a screw-threaded connection, as at 63, with the upper portion of the case or shell 60 and provided with a horizontal flange 64, which rests on the upper edge of the casing or shell 60 and to which the top plate or cover 56 is secured. Within the valve casing 62 a hollow valve 65 is rotatably mounted and is secured to a stem 66 having bearing in the lower end of the casing 62 and extending upwardly through a suitable bearing or collar 67 in the top portion of the valve 65 and also through an opening 68 in the top or cover plate 56. The top or cover plate 56 is projected any suitable distance towards the front in the form of an indicating segment 69 having opposite stop flanges 70 at the ends thereof and on its upper surface inscribed with characters which in the present instance consist of a cipher (0) and the numerals 1, 2, 3 and 4. Cooperating with this indicating segment and the characters thereon is a horizontally disposed valve lever 71 attached at its inner extremity to the upper end of the valve stem 66. The casing or shell 60 at its rear portion has a union 72 projecting rearwardly therefrom for connection of a pipe 73, which has its rear end in engagement with a collar or union 74 in the central portion of the front end of the chamber 12. The opening through the rear portion of the union is reduced, as at 75, and is wholly above the maximum level of the oil in the chamber 12, as shown by the dotted lines. Through the adjacent walls of the inner valve casing 62 and valve 65 are ports 76 and 77, the port 76 always standing in alinement with the inner terminal of the port 70. When the valve 65 is turned to certain positions, the ports 77 and 76 will be varied as to the opening space provided by the same relatively to the opening or port 75. An annular space or chamber 78 is formed between the valve casing 62 and the outer valve casing or shell 60, and this annular space is continuous with a lower chamber 79 between the bottom of the inner valve casing 62 and the outer casing or shell 60. Connected to the lower portion of the chamber 79 is a dry steam pipe 80, which as shown by Fig. 1 projects laterally and is continued by an angular branch 81, which in turn is secured to a cross return branch 82 connected to the unions 32 of the reduced dry steam forming pipes 29 and 30, and by means of which dry steam may be conveyed into the chamber 79 of the regulator and flow upwardly and pass outwardly through the port 75 with the vaporized hydrocarbon through the pipe 73 into the chamber 12, for a purpose which will be presently explained. The pipe 82 has a valve 83 therein, which may be adjusted to regulate the quantity of the dry steam passing through the bottom of the regulator 57 or into the chamber 79, or the supply of steam may be entirely cut off when the regulator is not in use. The valve 65, as hereinbefore indicated, may be adjusted to regulate the size of the openings between the registering ports 76 and 77 to entirely close off any registration of these ports, and the indicating characters on the segment 69 will give correct information as to the adjustment. When the lever 71 is turned fully over the cipher (0), the valve 65 will be closed, or the port 77 thereof will not register with the port 76. When the lever 77 is turned to register with the numerals 1, 2 and 3, the ports 76 and 77 will be opened, respectively, one-fourth, one-half and three-fourths, and when the said lever is turned fully over to register with the numeral 4, the ports 76 and 77 will have full registration, or be completely open.

At regular intervals over the upper portion of the body or main element 5 a plurality of burner units 84 are disposed and each unit consists of an outer shell 85 having an upper round or semicircular top 86 with perforations 87 formed therein. The lower extremity of the shell 85 has an integral stop collar 88 and exterior screw threads 89, which are adapted to separably engage the threaded collar 15 around the opening 14 and rising from the top plate or covering 13 of the oil chamber 12. The lower end of the shell 85 terminates coincidently with the lower side of the top cover or plate 13, as clearly shown by Fig. 3, and the said shell is of equal diameter throughout its extent. Within the shell 85 is a shell 90, of less diameter but of essentially the same contour, to produce an annular chamber 91 between the two shells, the upper rounded or semicircular end 92 of the inner shell being formed with perforations or openings 93. The lower portion of the inner shell 90 is diametrically reduced and provides a

lower tubular neck 94, which is exteriorly screw threaded, as at 95, to removably engage the threaded collar 18 of the bottom 16 of the oil chamber 12. The neck 94 of the inner shell 90 opens into the dry steam chamber 11 and passes through the quantity of oil in the chamber 12. There is, however, no direct communication between the oil chamber 12 and the dry steam chamber 11, 10 as the neck 94 of the inner shell 90 is imperforate. The annular chamber 91 between the two shells 85 and 90, however, is fully open at its lower terminal through the oil chamber 12, and by this means the oil vapor 15 is permitted to unrestrictedly pass upwardly between the two shells and the dry steam from the chamber 11 is free to pass upwardly into the inner shell, the dry steam and oil vapor mingling within the space between the upper semicircular ends or heads 86 and 92 of the respective shells in proper proportions to form an advantageous combustible heating medium. The upper extremities of the burner units 84 stand above 20 the adjacent pipes and these units as a whole will provide for an intense heating action within a furnace chamber for both domestic and general commercial usage. The shells 85 and 92 are readily removable from their 25 respective collars 15 and 18 for cleaning purposes and to give access to the chambers 12 and 11, and it will be understood that when necessary the said burner units may be replaced by similar new devices without 30 affecting the remaining burner units that may still be in practical working order. The pipes 27, 29, 30 and the vaporizing loop 54 are located between portions of the burner units, and the heat from the latter affect the 35 said pipes and vaporizing coil to effectively dry the steam and vaporize the oil when the vaporizing coil 54 is open for use.

Below the conveying oil pipe 52 supplemental burners 96 are horizontally disposed 40 and consist of burner tubes 97 having a plurality of upper openings 98. The burner tubes 97 are closed at their rear ends by suitable caps 99 and connected at their front ends to a T-shaped supply or cross branch 100 45 having a supply pipe 101 adapted to be connected to a gas main and provided with a valve 102, by means of which the gas from the main may be cut off as hereinafter more fully explained. The T-shaped or cross supply branch 100 also has a cross vapor pipe 103 with two outlet branches 104 opening 50 into the said T-shaped supply or cross branch adjacent to the outer ends of the burner tubes 97. The vapor pipe 103 is 55 connected by a supply pipe 105 with the top portion of the union or connection 72 for the pipe 73, which establishes an open way between the front portion of the chamber 12 and the regulator 57, this regulator 60 serving, as hereinbefore indicated, to admit 65

an auxiliary vapor supply to the several burner units, or, specifically, to the lower portions of the annular chambers 91, to supplement the vapor produced in the chamber 12. The pipe 105 will operate as a supply means relatively to the vapor connection for the tubular burners 97 even though the valve 67 may be closed and the conveying pipe 52 cut off through the medium of the valve 59, in view of the fact that the pipe 73 is open 70 to the chamber 12 and vapor from this chamber may pass into the pipe 105. In starting the improved burner organization it is proposed to use ordinary gas from a street service admitted through the pipe 101 and to the burner tubes 97. By this means the burner organization will be thoroughly heated and steam formed as well as oil vaporized in the respective chambers 10 and 12 and pass through the courses hereinbefore explained and into the burner units in such proportions as to produce a combustible heating medium, and if desired the burner tubes 97 may continue to act as heating 80 means with fuel supplied from a gas main, but it is preferred that after the burner organization as a whole has been caused to operate for some time to automatically produce hydrocarbon vapors and dry steam, the valve 101 be closed and the hydrocarbon vapor be fed to the said burner tubes by means of the pipe 105 and cross vapor pipe 103. By this means it will be seen that the burner organization will supply a heating medium 90 for the burner tubes 97 independently of any gas main, with economy in the heating 100 operation.

As hereinbefore indicated, the simplified operation of the burner organization will be through the medium of the burner units 84 independent of the vaporizing coil 54, the oil conveying pipe 52 being then cut off by closing the valve 59 and thereby also eliminating the regulator 57 controlling the auxiliary or supplemental supply of hydrocarbon vapor and dry steam. This simplified operation will be sufficient for ordinary domestic use, or in small domestic heating furnaces. In larger installations such as steam boilers, locomotive and marine engines it will be preferred to use the vaporizing coil 54 with the conveying pipe 52 in connection therewith and also the regulator 57 controlling the auxiliary supply or supplemental mixture, as hereinbefore explained, and regulable through the adjustment of the lever 71 and valve 65. In some instances the simplified form of the burner organization will be used without the vaporizing coil 110 115 120 125 130 135 54 and connections therefor and the regulator 57, it only being necessary to close the openings where the several parts of this auxiliary attachment are connected by means of caps or screw plugs without in the least modifying the simple operation of the

burner units, which will then be supplied with hydrocarbon vapor from the chamber 12 and dry steam from the chamber 11. In all instances, however, the pipes 27, 29 and 5 30 will be used for drying wet steam that is produced in the chamber 10, and in this simplified operation the use of burner tubes 97 may be discontinued after the said burners have served their purpose as a means for 10 starting the remaining parts of the burner organization in operation.

The several parts of the improved burner organization are of such dimensions that they may be readily installed in furnaces of 15 all types as now constructed, it only being necessary to provide openings through the sides of the burners for the insertion of the feed pipes from the oil and water reservoirs, and while one preferred construction and 20 arrangement of the improved burner organization is shown in the accompanying drawings and explained as being adapted for simplified and more complex operations, or wherein the vaporizing coil 54 may or may 25 not be used, it will be understood that it is proposed, also, to make such changes in the general proportions and dimensions of the several parts as to adapt the improved burner organization for service in any form 30 of furnace to which it may be applicable as a heating means.

What is claimed as new is:

1. A high pressure vapor oil burner, comprising a compact main element containing 35 a plurality of separated chambers respectively for water, dry steam and a hydrocarbon product, and a plurality of burner units connected to and extending above said element and communicating with the dry steam and hydrocarbon product chambers.

2. A high pressure vapor oil burner, comprising a compact main element containing a plurality of superposed separated chambers respectively for water, dry steam and a 45 hydrocarbon product, and a plurality of burner units connected to and extending above said element and communicating with the dry steam and hydrocarbon product chambers.

3. A high pressure vapor oil burner, comprising a compact main element containing a plurality of separated superposed chambers respectively for water, dry steam and a hydrocarbon product, a plurality of burner 50 units connected to and rising above said element and communicating with the dry steam and hydrocarbon product chambers, and primary heating means disposed below the bottom of the main element.

4. A high pressure vapor oil burner, comprising a compact main element containing a plurality of separated chambers respectively for water, dry steam and a hydrocarbon product, means for maintaining a uniform level of water and hydrocarbon prod-

uct in the chambers for the latter, and a plurality of burner units connected to and rising above the said element and communicating with the dry steam and hydrocarbon product chambers.

5. A high pressure vapor oil burner, comprising a compact main element containing a plurality of separated superposed chambers respectively for water, dry steam and a hydrocarbon product, means for automatically maintaining a uniform level of the water and hydrocarbon product in the water and hydrocarbon product chambers, and a plurality of burner units connected to said element and communicating with the dry steam and hydrocarbon product chambers, steam and vapor being formed in the water and hydrocarbon product chambers and commingling in the burner units.

6. A high pressure vapor oil burner, comprising a main element of cast metal having an upper and a lower section containing a plurality of separated superposed chambers respectively for water, dry steam and hydrocarbon product, and a plurality of burner units connected to said element and communicating with the dry steam and hydrocarbon product chambers.

7. A high pressure vapor oil burner, comprising a compact main element containing a plurality of separated chambers respectively for water, dry steam and a hydrocarbon product, and a plurality of burner units connected to said element and communicating with the dry steam and hydrocarbon product chambers, the said units being readily removable for cleaning purposes.

8. A high pressure vapor oil burner, comprising a compact main element containing a plurality of separated chambers respectively for water, dry steam and a hydrocarbon product, and a plurality of burner units connected to said element, each burner unit comprising an outer and inner shell respectively opening at their lower extremities into the hydrocarbon product and dry steam chambers.

9. A high pressure vapor oil burner, comprising a compact main element containing a plurality of separated chambers respectively for water, dry steam and a hydrocarbon product, and a plurality of burner units connected to said element, each burner unit comprising outer and inner shells with a space between them and the said shells respectively communicating with the hydrocarbon product and dry steam chambers.

10. A high pressure vapor oil burner, comprising a compact main element containing a plurality of separated superposed chambers consisting of a lower water chamber, an upper hydrocarbon product chamber and an intermediate dry steam chamber,

and a plurality of burner units having outer and inner shells respectively and independently communicating with the hydrocarbon product and dry steam chambers.

5 11. A high pressure vapor oil burner, comprising a compact main element containing a plurality of separated superposed chambers respectively for water, dry steam and a hydrocarbon product, and a plurality 10 of burner units connected to said element and each having an outer shell and an inner shell of materially less diameter than the said outer shell, the inner shell extending below the lower end of the outer shell and 15 the two shells respectively communicating with the hydrocarbon product and dry steam chambers.

20 12. A high pressure vapor oil burner, comprising a compact main element containing a plurality of separated superposed chambers respectively for water, dry steam and a hydrocarbon product, conduit means 25 connected to the water chamber and extending upwardly and over to the front of the said element and reduced in diameter and connected to the said dry steam chamber, and a plurality of burner units connected to said element and independently communicating with the hydrocarbon product and 30 dry steam chambers.

35 13. A high pressure vapor oil burner, comprising a compact main element containing a plurality of separated superposed chambers respectively for water, dry steam and a hydrocarbon product, conduit means 40 connected to the water chamber and extending upwardly and over to the front of the said element and reduced in diameter and connected to the said dry steam chamber, a plurality 45 of burner units connected to said element and independently communicating with the hydrocarbon product and dry steam chambers, and heating means disposed below the bottom of the main element and operable both at intervals and continuously to heat the said element and the contents thereof.

50 14. A high pressure vapor oil burner, comprising a compact main element containing a plurality of separated superposed chambers respectively for water, dry steam and a hydrocarbon product, steam conveying 55 means connected to the water chamber and extending upwardly and rearwardly, forwardly and again rearwardly over the top portion of the element and reduced in diameter and also connected to the dry steam chamber, and a plurality of burner units connected to said element and respectively 60 and independently communicating with the hydrocarbon product and dry steam chambers.

65 15. A high pressure vapor oil burner, comprising a compact main element containing a plurality of separated superposed

chambers respectively for water, dry steam and a hydrocarbon product, steam conveying means connected to the water chamber and extending in reverse directions over the element and also reduced in diameter lengthwise thereof and connected to the dry steam chamber, means for automatically maintaining a uniform level of water and hydrocarbon product in the chambers therefor, and a plurality of burner units connected to said element and having two parts with an intervening annular chamber, the said parts respectively and independently opening into the hydrocarbon product and dry steam chambers.

70 16. A high pressure vapor oil burner, comprising a compact main element having a plurality of separated chambers respectively for water, dry steam and a hydrocarbon product, a plurality of burner units connected to said element and communicating with the dry steam and hydrocarbon product chambers, conduit means connected to the water chamber and extending upwardly and rearwardly, forwardly and again rearwardly over the top of the said element and reduced in diameter and connected to the dry steam chamber, an oil supply means having a conveying pipe extending upwardly and thence alternately back and forth 80 over the top of the element, regulating means with which the said conveying pipe is connected, the regulating means having communication with the hydrocarbon product chamber, and a plurality of burner units connected to and rising above the top of the element and respectively and independently communicating with the hydrocarbon product and dry steam chambers.

both at intervals and continuously to heat the said element and the contents thereof.

18. A high pressure vapor oil burner, comprising a compact main element containing a plurality of separated superposed chambers respectively for water, dry steam and a hydrocarbon product, conduit means connected to the water chamber and extending upwardly and thence alternately 5 back and forth over the top of the said element and reduced in diameter and connected to said dry steam chamber, a vaporizing pipe disposed over the top of the said element, a hydrocarbon product reservoir connected to said vaporizing pipe, a regulator connected to the hydrocarbon product chamber and also having the said vaporizing pipe attached thereto, a pipe connection between a portion of the said conduit means 10 and the regulator, and a plurality of burner units connected to and rising above the top of said element and respectively and independently communicating with the hydrocarbon product and dry steam chambers.

20. 19. A high pressure vapor oil burner comprising a main element containing a plurality of separated superposed chambers respectively for water, dry steam and a hydrocarbon product, conduit means connected 25 to the water chamber and extending upwardly from the latter and thence alternately back and forth over the top portion thereof and reduced in diameter, the said conduit means being connected to the dry 30 steam chamber, a vaporizing pipe over the top of the element and connected to the said hydrocarbon product chamber, heating means disposed below the bottom of the said element and having a supply connection 35 for fuel from a gas main and also a connection with a portion of the regulator for conveying mixed hydrocarbon vapor and dry steam thereto, the said heating means 40

being operable both at intervals and continuously to heat the said element and the 45 contents thereof, and a plurality of burner units connected to and rising above the top of the said element and respectively and independently communicating with the hydrocarbon product and dry steam chamber. 50

20. A high pressure vapor oil burner, comprising a compact main element containing a plurality of separated chambers respectively for water, dry steam and a hydrocarbon product, steam conveying means connected to the water chamber and extending upwardly and thence alternately back and forth over the top portion of the element and reduced in diameter and also connected to the dry steam chamber, a hydrocarbon 55 vaporizing pipe disposed over the element and having means for supplying the same with hydrocarbon product, a regulator with which the vaporizing pipe is connected, the regulator also having communication with 60 the hydrocarbon product chamber, a plurality of burner units connected to and rising above the top of the said element and respectively and independently communicating 65 with the hydrocarbon product and dry steam chambers, and heating means disposed below the bottom of the said main element and having a pipe connection with a portion 70 of the regulator to receive a mixture of hydrocarbon product vapor and dry steam, the 75 said heating means also having a connection for supply of gas thereto from a main, the regulator and hydrocarbon product vaporizing pipe being provided with means for cutting the same off from the remaining 80 parts of the burner and the heating means being adapted to be cut off from the gas main supply.

In testimony whereof I have hereunto set my hand.

SALVATORE SCOGNAMILLO.
